UNITED STATES PATENT OFFICE.

CHARLES C. SCHNEIDER, OF ST. LOUIS, MISSOURI, ASSIGNOR OF ONE-HALF TO JAMES H. CUTTER, OF ST. LOUIS, MISSOURI.

APPARATUS FOR LAYING AND PILING CLOTH.

1,036,011.

Specification of Letters Patent. Patented Aug. 20, 1912.

Application filed January 21, 1911. Serial No. 603,994.

To all whom it may concern:

Be it known that I, CHARLES C. SCHNEIDER, a citizen of the United States, and resident of St. Louis, Missouri, have invented 5 certain new and useful Improvements in Apparatus for Laying and Piling Cloth, of which the following is a specification.

This invention relates to improvements in an apparatus for laying and piling cloth 10 and has for its object a carriage operating on a table spreading the cloth in long layers and a catching device for holding the cloth at the end of the run so as to permit the carriage to be reconveyed and in this repeated 15 action the cloth is laid and piled to any desired height.

A further object of my invention is to provide a carriage to operate on a table and guided on one track rail for spreading layers 20 of cloth and piling it, and to operate a catching device for supporting the cloth at the ends of the run, and these catching devices automatically operated when contacted with by the carriage.

Figure 1 is a side elevation of the carriage. Fig. 2 is the reverse side of the same. Fig. 3 is a central, sectional view. Fig. 4 is a top plan view of the same. Fig. 5 is an enlarged detail side elevation of the cloth 30 laying roller frame, and its automatic adjusting means. Fig. 6 is an enlarged, detail, sectional view of the dog and ratchet by which the roller frame is adjusted. Fig. 7 is an enlarged, detail, fragmental, sectional 35 view of the rollers showing their telescopic connection. Fig. 8 is an enlarged, detail, fragmental view of one of the telescopic cross-bars made use of in carrying out my invention. Fig. 9 is a detail sectional view 40 of the caster made use of for supporting one side of the machine while in the act of the adjustment to various widths. Fig. 10 is a side elevation of the carriage and the cloth catching device in their relative operative 45 position on the table. Fig. 11 is a top plan view of one member of the catching device with a part thereof broken away and in section. Fig. 12 is a side elevation of the same. Fig. 13 is a detail view of one of the hook 50 operating arms for spreading the hooks of the catcher. Fig. 14 is a sectional view of a portion of the clamping bar, which supports the catching device on the table. Fig. 15 is

a detail perspective view of one of the sockets made use of in supporting the board 55 containing the bolt of cloth. Fig. 16 is an end view of a socket made use of for supporting the opposite end of the board.

In the construction of my invention I provide a carriage 17 constructed of two 60 sides 18 and 19, and which are mounted on wheels or rollers 20. The wheels on the side 18 are preferably grooved so as to ride upon a track or rail located on the table 21, and by the same the carriage is guided in 65 proper alignment. The sides 18 and 19 of the carriage are supported together by a plurality of telescopic cross-bars 22 consisting of blocks 23 securely fastened to the sides 18 and 19, and in said blocks is provided a dovetailed recess 24 in which is inserted and operates the dovetailed connecting bar 25.

To the side 18 are connected screwthreaded rods 26 with which engage the internally 75 screwthreaded sleeves 27 which are carried by the side 19 and project through the same, having on their outer ends sprocket wheels 28 over which the sprocket chain 29 operates, the forward sprocket wheel having a 80 projecting squared end over which is placed the crank handle 30, and by the same the chain is placed in operation revolving the sleeves 27 simultaneously, acting upon the screwthreaded rods 26, and in this manner 85 causing the carriage to be adjusted to any desired width required for the laying of various widths of cloth. The sides 18 and 19 also support arms 31, which carry telescopic rollers 32 and 33, over which the 90 cloth is passed as shown by dotted lines in Fig. 3. These arms are pivotally connected to the sides and are held in any desired tilted position on the segments 34. The rear end of the carriage is provided with brackets 95 35 in which are supported the trunnions of the socket pieces 36 and 37 when it is desired to lay cloth that has been wrapped up in a bolt (see Figs. 1, 15, and 16). The forward end is provided with a plurality of 100 telescopic rollers 38, 39, 40, 41, and 42. These rollers are supported in brackets and over the same is passed the cloth as shown by dotted lines in Fig. 3.

To the sides of the carriage and near the 105 forward end is pivotally attached a roller

adjusting frame, which consists of horizontal bars 43 and 44 pivotally connected to the sides of the carriage at the points indicated by the numeral 45, and at the pivotal point 5 of the bar 43 is attached a hand lever 46. Connected to the pivotal end 45 of the bar is the telescopic connecting bar 47, the opposite end of said bar communicating with the corresponding bar 44 on the opposite side, 10 and by the manipulation of the hand lever 46 by means of its link connection 48 the horizontal bars 43 and 44, together with the rollers carried thereby can be adjusted to the position as shown by dotted lines in 15 Fig. 5, the forward or free ends of the bars being provided with a bracket 49 to which is supported telescopic rollers 50, 51 and 52 over which the cloth is passed as shown in Fig. 3, and the two forward rollers 51 and 20 52 are what is termed the cloth laying rollers.

The bar 44 is provided with a screw-threaded adjusting bolt 53, which operates with the internal screwthreaded ratchet 25 wheel 54 mounted and supported on the pocket 55 in which operates a barrel 56 having at its under end a roller 57, the same being arranged to contact during the movement of the carriage with the inclined surface 30 58 of the guide rail 59 and after the roller 57 rides up the inclined surface 58 it automatically raises the frame, together with the cloth laying rollers to a position as shown by the light dotted lines in Fig. 5. 35 During the upward movement the ratchet wheel 54 simultaneously raises with the frame. The object of the raising feature will be fully, hereinafter described.

On the side 18 is mounted a bracket 60 in 40 which is supported a sliding bolt 61 having its forward end formed into a tooth or dog 62, said tooth arranged to contact with and operate the ratchet wheel 54, (see Fig. 6).

Reciprocatory movement is imparted to 45 the bolt 61 by the bifurcated lever 63 pivoted to the side at the point indicated by the numeral 64 and to the opposite end of the lever is pivoted the pawl 65, its tooth 66 arranged to contact with the projection 67 50 formed on the guide rail 59, and this operation is accomplished by means of the integral ear 68 of the pawl contacting with the edge of the bifurcated lever, (see Fig. 5).

During the rearward movement of the 55 carriage the pawl 65 is permitted to operate idly, and by each reciprocatory movement of the bolt 61 the ratchet wheel 54 is operated, automatically raising the frame a slight distance higher. The purpose of this 60 is to provide for the thickness of a number of layers of cloth piling on the table, and thus permitting the cloth laying rollers to operate freely and without friction on the pile of cloth.

65 On the side 19 of the carriage I provide

a caster 69 consisting of a housing 70 having a slotted front face, the surface being provided with serrations or teeth 71 with which the spring actuated handle 72 contacts, and which is carried by the roller bar 73, (see Fig. 9).

When it is desired to adjust the width of the carriage, in order to regulate the same to correspond with the width of the goods to be laid, the operator, prior to the manipulation of the crank 30 presses the caster downwardly so that its roller contacts with the table, and by partially raising the carriage on this side the caster will have a tendency to keep the wheels on said side above the table, and in this manner the entire weight of the one side of the carriage is supported on the caster, and then by the manipulation of the handle 30 the carriage can be readily and easily adjusted in width.

To disengage the caster from its operative position, the handle 72 is manipulated by being drawn outwardly away from the teeth, and the roller bar is raised in its normal position by means of the spring 74.

On each end of the table, or otherwise located in operative connection with the carriage, I place my improved catching devices by which the cloth is held at the end of the pile. The catching device consists of a pair of bars 75 pivotally connected to ears 76 formed on a supporting bar 77. The two bars 75 are connected together by the telescopic connection 78 and by the manipulation of the same, by means of the handle 30 taken from the carriage, the screw 79 of the connection is operated and the width of the frame comprising the catcher can be adjusted.

The bar 75 is provided with grooves 80 in 105 which operate the horizontal portion 81 of the arm 82 and the same is held in its forward position by means of the spring 83 connecting the lug 84 projecting from the arm 82 with the bar 75. The forward end 110 of the portion 81 is provided with a perforated projection 85, which operates over the hook arm 86.

Both of the bars 75 are provided with hook arms 86 which are pivotally connected 115 to the bars at the point indicated by the numeral 87. These arms are extended in the position as shown by dotted lines in Fig. 11. When the bracket 49 of the carriage is brought in contact with the ends 88 of the arms 82 pressing the same rearwardly, at the same operation the action of the projections 85, carried by the horizontal portion 81 causes the hook arms 86 to operate outwardly on account of the relative bend in 120 the arms. The object of spreading the hook arms is to permit the cloth to pass into the forward end of the catcher and on the return movement of the carriage, and immediately after the arms 82 have been released, 125 130

the hook arms return to their normal position contacting with the cloth, holding the same while the carriage is performing the same action on the opposite end of the table.

5 Whereas in the construction of the companion catcher on the opposite end of the table, the projecting arm of the frame 82 is dispensed with and the operation of the hook arms is accomplished by the contacting of 70
10 the bracket 89 secured to the under side of the forward cross-bar with the projecting arm 90, (see Fig. 10).

While the cloth is being piled upon the table it is necessary to regulate the height of 15
15 the hook arms in accordance therewith so as to perform accurate and operative results. This required adjustment is accomplished by providing the cams 91 on a telescopic connection 92, one end of the connection projecting through one of the bars 75 provided with a ratchet wheel 93 with which the pawl 94 engages, and by the manipulation of the handle 95 carried by one of the cams the bar 75 together with the catching device sup-

25 ported thereon is raised to the proper height required. The catching device is supported on the table by means of the clamp 96, and the horizontal adjustment of the catcher to correspond with the width of the cloth is 30
30 accomplished by the adjusting screw sliding one of the bars 75 along the guide rod 97 and the guide block 98 operating in the slot formed in the bar 77, (see Fig. 11).

Each of the telescopic rollers (enlarged 35
35 detail view of the same being shown in Fig. 7) are constructed of an inner tube 99 and an outer tube 100, each of which is provided with the flange 101 which acts as a guide to prevent the cloth from becoming displaced.

40 By referring to Fig. 3 I show the cloth in dotted lines located in its relative position upon the carriage and the position it assumes around the several rollers, but in the event a bolt of cloth is supported in the 45
45 brackets 35 the end is passed under the roller 32 and over the roller 33 and continued on in like manner as shown by dotted lines.

The essential feature in laying cloth by a 50
50 machine of this character is the laying and piling of cloth evenly and to support the looped ends, keeping the cloth in taut position while the carriage is being operated, and to have an automatic adjusting device 55
55 whereby the laying rollers regulate themselves automatically in accordance with the height of the pile.

The operation of my invention is as follows: The cloth is laid in the machine either 60
60 in the form of a flat bundle, as shown by dotted lines in Fig. 3, or a bolt as shown by dotted lines in Fig. 1. The end of the cloth is passed over the several rollers as indicated by dotted lines in Fig. 3, the carriage is con- 65
65 neyed to one end of the table and the end of

the cloth retained in position at that end in any desirable manner until the carriage has made its first trip to the opposite end of the table. As the carriage contacts with the catcher at that end, the hook arms are extended outwardly and then operate inwardly retaining the looped end of the cloth in position while the carriage is making its trip to the opposite end of the table, the same operation of the catcher at that end 75
75 prevails.

During each operation the frame carried by the carriage supporting the cloth laying rollers contacts with the incline surface 58 of the rail 59 automatically raising the cloth laying rollers to a proper height so as to freely pass over the hook arms, and so as to permit the hooks to pass beneath the rollers between the same and the cloth, and during each forward movement of the carriage the 80
80 pawl 65 when contacting with the projection 67 operates the raising mechanism. In this manner the cloth is piled to the required height in an even and accurate pile.

Having fully described my invention, 90
90 what I claim is:

1. An apparatus for laying and piling cloth, comprising a carriage on which the cloth is mounted, means for adjusting the width of the carriage, a frame supporting 95
95 cloth laying rollers carried by the carriage, in combination with a catching device mounted upon the table and in alinement with the carriage, hook arms carried by the catching device and operated automatically 100
100 with the contacting of the carriage, and means whereby the frame and cloth laying rollers are automatically elevated when contacting with the catcher, substantially as specified.

2. An apparatus for laying and piling cloth, comprising a carriage upon which the cloth is mounted, telescopic rollers mounted on the carriage over and under which the cloth is passed, a frame pivotally mounted 110
110 on the end of said carriage, cloth laying rollers carried by said frame, means for elevating the frame and rollers, in combination with catchers mounted on a table on which the carriage operates, means for retaining 115
115 the ends of the cloth while the carriage is being operated forwardly and rearwardly, and means for automatically adjusting the height of the cloth laying rollers to correspond with the height of the pile of cloth, 120
120 substantially as specified.

3. In a device of the class described, the combination of a carriage mounted on a table and a catching device located on each end of said table in alinement with the carriage, means for adjusting the width of the carriage and the catching devices so as to correspond with the width of the cloth to be laid and piled, cloth laying rollers adjustably mounted on the carriage, means for op- 125
125
130

- erating the catching devices automatically with the contacting of the carriage, and means for elevating the catchers so as to correspond with the height of the pile of cloth, 5 substantially as specified.
4. In a device of the class described, the combination of a carriage and a table on which the same is mounted, of catching devices located on each end of the table and 10 arranged to receive and hold the cloth when delivered by the carriage, telescopic cross-bars forming the carriage body, telescopic rollers mounted on the carriage frame over which the cloth is passed, an adjusting device 15 whereby the width of the carriage is regulated to correspond with the width of the cloth to be laid and piled, a frame pivotally mounted to one end of the carriage, cloth laying rollers carried by said frame, 20 an adjusting device for regulating the width of the catching devices to correspond with the width of the carriage, hook arms pivotally carried by the catching devices, means for operating the same when contacted with 25 by the carriage frame, and means for automatically raising the cloth laying rollers above the hook arms so as to permit the cloth to pass around the hooks and form a loop, and means for raising the frame on 30 the carriage supporting the cloth laying rollers, and means for raising the catching devices to correspond with the layers of

cloth piled on the table, substantially as specified.

5. In a device of the class described comprising a carriage arranged to travel on a table, cloth laying rollers adjustably mounted on said carriage in combination with catching devices, automatically operated by the contacting of the carriage and screws 40 for regulating the width of the carriage to correspond with the width of the cloth to be laid, substantially as specified.

6. In a device of the class described comprising a carriage arranged to travel on a table and adjusting screws whereby the width of the carriage is regulated according to the width of the cloth to be laid, cloth laying rollers carried by the carriage, means for automatically raising the cloth laying 50 rollers in accordance with the increase of height in the layers of cloth, in combination with a catching device, means carried on the catching device to grip the ends of the cloth and automatically operated when contacted with by the carriage, substantially as specified.

In testimony whereof, I have signed my name to this specification, in presence of two subscribing witnesses.

CHARLES C. SCHNEIDER.
